FRED H. BANKERT, OF OTTAWA, ILLINOIS, ASSIGNOR TO CHICAGO RETORT AND FIRE
BRICK COMPANY, OF CHICAGO, ILLINOIS, A CORPORATION OF ILLINOIS.

BRICK-PRESSING MACHINE

Application filed February 23, 1926. Serial No. 89,858

My invention relates to machines for
pressing brick and provides a machine for
this purpose in which by means of a single
pressing operation on each brick, bricks of
uniform thickness and relatively uniform
density are produced. Though my invention
is applicable to the production of all
kinds of brick it is particularly useful in
connection with the production of fire brick
10 for the reason that uniform thickness is
especially desirable therein because it avoids
the use of an excess of cement in laying the
brick. It is well known that in fire brick
constructions the cement in which the bricks
15 are laid is destroyed or deteriorated much
more rapidly than the fire bricks themselves,
and therefore it is desirable to restrict the
amount of cement to the least that can be
employed and this can best be attained by
20 providing bricks which are as uniform as
possible in thickness and the surfaces of
which are as nearly plane as they can be
made.

25 In my improved brick press, which may otherwise be of usual or approved construction, I provide a shaving or trimming blade so arranged in the path of the pusher by which the clots or blocks of material which are to form the brick are fed to the press box or chamber, that the clots are caused to pass under the blade and are thereby trimmed or shaved to a uniform thickness before being received by the press box. As the dimensions of the clots are otherwise uniform they are thus caused to contain a uniform amount of material, with the result that after being pressed they are uniform in dimensions and density or vary only in the smallest degree. Provision is made for the adjustment of the trimmer so that the thickness of the clots after trimming may be varied and further provision is made for ejecting any shavings or fragments of material from the machine and preventing them from entering the press box with the following brick blocks or clots.

In the accompanying drawings I have illustrated my invention as applied to a well-known form of brick press, but it will be obvious from the following description that it is applicable to a variety of presses, and while I have specifically described it hereinafter in connection with the form of press shown, it is to be understood that I have done so for the purpose of exemplification.

only and that the invention is not limited to the specific form shown but only as it is defined in the following claims.

In the drawings, Figure 1 is a side elevation of the form of press chosen for the purpose of illustration with my invention applied thereto; Fig. 2 a longitudinal section on an enlarged scale of so much of said press as is convenient for an explanation of the invention; Fig. 3 a plan of the machine partly in horizontal section; Fig. 4 an end view thereof, and Fig. 5 a transverse section of a portion of the machine on an enlarged scale.

Describing first the known form of press chosen for the illustration of my invention, it comprises a main frame 6 having a press box or chamber 7 and a bed or track 8 over which latter the clots or blocks of brick forming material are fed to the press box. The press box is open at its upper and lower ends through which extend the respective plungers 9, 10, carrying respectively the platens 11, 12 which closely fit within the chamber and are reciprocable to compress the clots as they are successively fed to the press box to give the bricks their ultimate shape. In the form of machine illustrated the lower plunger 10 is suitably guided and it is reciprocated by means of a cam 13 operating on roller 14 carried by said plunger. In the particular machine shown, which is adapted to act upon two clots or blocks at the same time, there are twin pressing boxes each equipped with plungers and platens as described. The lower plungers are connected to a common head 15 which is suitably guided for vertical reciprocation in the machine. The above mentioned cam 13 is carried by a cross-shaft 16 mounted in the frame. The upper plungers 9 are connected to a cross-head 20 which is guided for vertical movements in slotted standards 21.

The cross-head 20 is formed with trunnions 22 journaled in blocks 23 on the ends of links 24, springs 25 yieldingly holding the members of the blocks 23 together so that there may be a slight yield in case of necessity to avoid breaking the machine, and also to provide an even pressure upon the bricks. The lower ends of the links 17 are pivoted respectively on wrist pins 26 carried by gear wheels 27 mounted on the above mentioned shaft 16 which carries the cam for operating the lower plungers. There

are two of the gear wheels 27 arranged respectively on opposite sides of the machine and both driven from a common shaft 28 carrying pinions 29 meshing with the respective gear wheels, said shaft being driven by a pulley 30. The shape of the cam and its relation to the wrist pins through which the upper plungers are driven are such that the platens 12 are raised to receive clots, after which the upper platens descend, compressing the clots and shaping them against the walls of the press boxes, following which the lower platens rise to permit the removal of the formed brick and to receive new clots for pressing.

As usual in machines of this type, a reciprocating pusher or follower 31 is provided to receive the clot or clots to be pressed and feed them to the press box successively. The follower is formed with ears 32 provided respectively with horizontal slots 33 for the reception of pins 34 upon the front ends of the links 35. The latter are connected at their rear ends to the fork 36 which is mounted on a small countershaft 37 journaled in the frame. The ends of said shaft are provided respectively with castings 38 having transverse sleeves 39 to receive the adjustable arms 40. Set screws 41 are provided for holding the arms 40 in adjusted position. The free ends of arms 40 carry pins 42 to which are pivoted the links 43, likewise arranged, respectively, on opposite sides of the machine. The other ends of links 43 are pivoted on the pins 26, previously mentioned. Thus at each reciprocation of the plungers of the press and at the proper time with relation to the movements thereof, the pusher is given a reciprocation. In the machine illustrated this occurs after each pressing operation when the lower plunger has arrived at such a position that its top face is in the plane of the upper face of the bed, so that the arrival of the follower or pusher with the new clots in front of it forces the pressed bricks from the face of the plungers and replaces them by fresh clots. A conveyor 44 receives the pressed bricks as they are ejected or removed from the face of the lower plungers and carries them away for suitable disposition.

As thus far described, the press is only of a well-known form. According to my invention and in carrying the latter out, the press is provided with a trimmer or shaving knife extending across above the bed and above the path of the pusher, and both bed and pusher are modified as hereinafter described to permit of their proper cooperation with the trimmer. The latter comprises a blade or knife-edge 46 mounted at an incline on the lower face of the knife bar 46^a carried by adjusting bar 47. The latter is vertically adjustable at its ends in slotted standards 48 provided respectively with adjusting

screws 49. The knife blade is of a length to shave both of each pair of bricks fed at a time by the pusher and the bar is cut away at 51 beyond the ends of the knife to provide for the free movement thereunder of the lugs 70 on the pusher and the actuating links connected thereto. The pusher comprises a U-shaped plate or member 52 which is provided at its opposite edges with slide flanges 53 projecting into rabbets in guide rods 54 75 extending lengthwise of the machine on opposite sides thereof. By this construction the follower or pusher is guided in its movements toward and from the press chamber.

In order to dispose of the material scraped or shaved from the clots and to prevent such material interfering with the operation of the press, the lower face of the pusher is spaced away from the upper face of the bed 85 as at 55 and the front edge of the pusher is provided with a wiper 56 of flexible material of sufficient rigidity to maintain contact with the face of the bed and sweep the shavings, etc., therefrom. The bed is cut away at 57 so that the wiper will discharge any shavings ahead of it at its extreme forward movement, and furthermore the bed is slotted transversely at 59, to permit the discharge through the slot of any material 90 which falls back of the wiper. If the press box is formed in a separate casting from the body of the frame as in the construction illustrated, this slot may be left between the adjacent edges of the castings, as shown in Fig. 3.

As heretofore stated, the knife or trimmer bar is adjustable for blocks or clots of different thickness and it is preferable to form the pusher in two vertically interposed sections, as shown in Fig. 2, the upper of which, 61, is bolted to the lower. The upper section may be exchanged for one of a different thickness when bricks of different thickness are to be made.

An inclined table 62 may be employed for convenience of the operator in placing the blocks or clots to be pressed in proper position to be engaged by the pusher. It may be provided with a rib 63 somewhat wider than the space 64 between the press chambers to further assist the operator in properly adjusting the bricks, and for the same purpose the pusher may be provided with a similar rib 65.

Any suitable means may be used for receiving the scrapings or trimmings discharged through the notch 57 and the slot 59. If desired the table 62 may be provided with an under-shelf 66 up which the shavings or trimmings will be forced by the wiper.

The operation of the machine has been described in connection with the description of the construction but may be summarized as follows: When the pusher is in the extreme 130

position shown in Fig. 2 the operator places a couple of clots or blocks to be pressed in position behind the same and on opposite sides of the rib 65. The pusher then moves forward and the brick and pusher pass under the knife or trimmer which shaves any and all excessive material from the top of the brick. The continued movement of the pusher brings the front faces of the clots thereon into contact with the last brick pressed which has in the meantime been raised to the level of the bed by the lower plunger, and further movement of the pusher displaces the brick and brings the clots into proper position on the platen 12. The bricks are conveyed away or removed from the press. The lower platen then descends into the box and the upper platen follows it and the clot is compressed between the two to form brick of the desired size, after which the operation is repeated. The bulk of the trimmings or shavings from the brick fall behind or in rear of the pusher and are discharged in the next backward movement thereof. Any material which falls in front of the pusher is discharged through the slot 59 on the next forward movement of the pusher.

By the use of my improvement, the clots which are otherwise of uniform dimensions are reduced to uniform thickness, the knife being so set as to remove a thin shaving from all of the clots except, perhaps, the very thinnest of them. Each clot, as it goes through the press, therefore, contains within the narrowest limit the same amount of material as every other clot, therefore the bricks, after pressing, are of uniform size. Furthermore by reason of the identity in the amount of material in all of the bricks the press acts upon all of them with the same pressure so that the formed bricks are identical in density and since equal amounts of clay are fed to the press for each stroke, clay of greater stiffness may be used than heretofore, and the finished brick being stiffer and stronger are not so apt to settle on the drier car as would otherwise be the case.

I claim:

1. In a brick press, a frame, a press box carried thereby, plungers cooperating with the press box for pressing clots to form

bricks, a bed-plate, a pusher reciprocating over the bed-plate and adapted to receive and feed clots to the press box, a trimmer blade mounted above the bed-plate and adapted to trim clots passing thereover and to drop the material removed therefrom onto the bed-plate, and means on the pusher for removing such material from the bed-plate. 55

2. In a brick press, a frame, a press box mounted on the frame, plungers cooperating with the press box for pressing bricks, a bed-plate over which clots to be pressed are movable, a pusher for moving the clots over the bed-plate to the press box, a trimmer blade mounted over the bed-plate and beneath which clots to be pressed are carried by the pusher, the blade being adapted to drop material removed from the clot onto the bed-plate, and a wiper on the pusher adapted to discharge material trimmed from the clots from the front end of the bed-plate. 60

3. In a brick press, a frame, a press box carried thereby, plungers cooperating with the press box, a bed-plate, a pusher movable over the bed-plate to feed clots to be pressed to the press box, a trimmer mounted above the bed-plate, the bed-plate being slotted intermediate the trimmer and the press box, 75 and a wiper on the pusher adapted to discharge material dropped from the knife on the bed-plate behind the pusher through the slot in the bed-plate. 80

4. In a brick press, a frame, a press box carried thereby, plungers cooperating with the press box, a pusher movable over the bed-plate, a trimmer blade adjustably mounted above the bed-plate and adapted to trim brick carried thereunder by the pusher, and means to vary the thickness of the pusher. 85

5. In a brick press, a frame, a press box, a bed-plate, plungers cooperating with the press box, a pusher movable over the bed-plate but spaced therefrom, a trimmer blade 95 mounted above the bed-plate and adapted to drop material trimmed from the clots onto the bed-plate, and a wiper mounted on the pusher and adapted to discharge material dropped by the trimmer blade onto the bed-plate from the latter. 100

In testimony whereof, I have subscribed my name.

FRED H. BANKERT.
